UNITED STATES PATENT OFFICE.

LOUIS PELTON, SARAH PELTON, AND FREDERICK E. FLEURY, OF CHICAGO, ILLINOIS.

BATHING-SUIT.

1,093,354.

Specification of Letters Patent. Patented Apr. 14, 1914.

Application filed November 13, 1911. Serial No. 659,967.

To all whom it may concern:

Be it known that we, LOUIS PELTON, SARAH PELTON, and FREDERICK E. FLEURY, citizens of the United States, residing at 5 Chicago, in the county of Cook and State of Illinois, have invented certain new and useful Improvements in Bathing-Suits, of which the following is a specification.

One of the objects of this invention is to 10 combine or unite the waist, skirt and bloomers of a bathing suit into a single garment, and thus render the operations of donning and connecting together the several parts more convenient and expeditious.

15 Another object of the invention is to produce a lady's bathing suit that when worn will be suspended entirely from the shoulders of the wearer, so that the great weight due to the wet garments and the water retained by the garments may be comfortably supported, and so that such weight shall not displace the garments. And it has the further object of arranging the openings of 20 the lower garments in such a manner as to prevent undesirable gaping in case one or 25 both of such garments should become partly or entirely unbuttoned.

In the particular embodiment of our invention which we have illustrated, and 30 which we will describe, Figure 1 of the accompanying drawings is a perspective view of the bathing suit, with a portion of the front of the skirt removed to disclose the undergarment. Fig. 2 is an enlarged trans- 35 verse section of the front portion of the suit along lines 2 2 of Fig. 1. Fig. 3 is an enlarged fragmental vertical section of the front portion of the suit along the line 3 3 of Fig. 1. And Fig. 4 is a front view of a 40 portion of the suit showing special features.

The waist 1 of the suit may be of any suitable material or style. In this instance we have shown the opening 2 of the waist as extending at one side of the front medial 45 line from the neck to the belt, including both. This opening is closed by a fly 3. On the other side of the front medial line is a band or plait 4 corresponding in appearance and symmetrical in position to the edge of 50 the fly 3. The opening 2 is closed by means of button-holes and buttons 5 underneath the fly 3. Permanently attached to the waist is a pair of bloomers 6, also of any suitable material and style. The bloomers 55 have, in this instance, an opening 12 which extends from the belt downward along the

front medial line, so that the bloomers may be opened sufficiently at the waist to pass up over the hips. This opening is closed by a placket 12^a extending from, say, the left 60 to the right and secured in place by buttons 7. Also attached permanently to the waist, either integral therewith or sewed to the waist belt 8, is a skirt 9. The skirt also has an opening 13 extending part way down 65 from the waist line, this opening being in line with and a continuation of the opening of the waist. In this instance, the openings 12 and 13 are of approximately the same length. The opening 13 is closed by a lap 70 or fly 11 extending from right to left, which fly forms in appearance, and is or may be in fact, a continuation of the fly 3 of the waist. The fly 11 is secured in place by suitable button-holes and buttons 10 which are underneath the fly 11. 75

As the opening of the skirt is at one side of the opening of the bloomers, in case of the skirt becoming opened inadvertently the fastenings of the bloomers will not be disclosed; and even though both openings should become unbuttoned at the same time, there would be no exposure of the person. The lap or fly of the opening of the waist and of the skirt, in this instance, extends 80 toward the left of the wearer, while the placket of the bloomers, as shown in the drawing, extends toward the right. This assists in keeping the double opening closed in case both garments become unbuttoned at 85 the same time. The exact position of these openings evidently is not material. The waist and the skirt might be opened along the medial line and the bloomers at either side thereof, or any other desired position 90 might be chosen for either of the openings, providing only that it were not opposite the other opening.

In putting on the suit all of the slits are 95 opened, the feet placed in the openings and the combined garment pulled upward over the body, the arms are then slipped into place and the various openings buttoned up.

The lower ends of the legs of the bloomers may be closed, as usual, with some elastic 100 material, or otherwise held closely about the legs; and, as is well known, when so held, the legs of the bloomers are likely to retain for some time after the wearer emerges 105 from the water considerable quantities of inclosed water in addition to that which is absorbed by the cloth itself. In such cases,

the suit is very heavy, and it is desirable to have the entire weight come on the shoulders. This is brought about, in this instance, by having both the skirt and the 5 bloomers attached directly to the belt of the waist. With this construction, the bloomers and the skirt cannot be displaced downwardly by their weight or the weight of the inclosed water.

10 We claim as our invention:

In a bathing suit, a pair of bloomers, a skirt, and a waist, said three garments being stitched together all of the way around the belt line, said bloomers and skirt each 15 having a single opening in the front portion thereof extending downwardly from the belt line and adapted to be spread to permit the suit to be drawn upwardly over the hips of the wearer, said openings being offset

from each other a short distance to prevent 20 exposure of person if both should be unfastened at the same time, a fly on the bloomers, and another fly on the skirt, said flies being arranged to overlap and close the openings in the respective garments, 25 said flies extending in opposite directions, and each fly extending away from the opening in the other garment.

In testimony whereof we hereunto affix our signatures in the presence of two witnesses.

LOUIS PELTON.
